UNITED STATES PATENT OFFICE.

HARRY H. BRIDENTHAL, OF LATROBE, PENNSYLVANIA.

ROAD-ENGINE.

SPECIFICATION forming part of Letters Patent No. 252,720, dated January 24, 1882.

Application filed June 22, 1881. (No model.)

To all whom it may concern:

Be it known that I, HARRY H. BRIDENTHAL, of Latrobe, in the county of Westmoreland and State of Pennsylvania, have invented new and useful Improvements in Road-Engines; and I do hereby declare the following to be a full, clear, and exact description thereof, reference being had to the drawings forming part of this specification, in which—

10 Figure 1 is a perspective view of my improved engine, parts being represented as broken away to show the construction of the gearing. Fig. 2 is a top or plan view. Fig. 3 is a rear elevation. Fig. 4 is a sectional elevation taken through the line $q-q$, Fig. 2, and shows the clevises for protecting the gearing from the mud and dirt thrown up by the traction-wheels. Figs. 5 and 6 are top and side views of the friction-chain, showing the arrangement and construction of the same. Fig. 15 7 is a detached view of the levers which operate the independent brakes, and Fig. 8 is a horizontal section of the equational gear and the arrangement of the brake-wheels and 20 brakes.

25 My invention relates more especially to that class of engines used for driving farm and other machinery that requires to be moved often, and the objects are to improve and adapt such engines for traction purposes also; and it consists in an improved carrying-frame and arrangement of main carrying-springs; in an arrangement of friction-chain speed-gears, whereby the relative speeds of the engine and 30 traction-wheels may be varied to suit the load drawn and the condition of the road; in combination of equational gear and independent brakes, and in an arrangement of slotted detachable sides or wheel-covers.

40 Similar letters and figures of reference denote like parts of the machine in all of the drawings.

45 The engine and boiler of my machine are constructed on the ordinary and well-known principles, hence need no special description here.

50 The boiler W is of the ordinary vertical type. The engine proper, D⁴, is also of the vertical type, and is firmly bolted to the forward side of the boiler with the cylinder end down, as shown, and as low as possible, so as to bring

the greater part of the weight of the whole machine as low as possible.

On the ends of the main carrying-axle o are formed long spindles, on which are hung loosely 55 the spur drive-wheels m and m' and the traction-wheels E E. A suitable linchpin or a collar is rigidly attached to the spindle between said spur and traction wheels, and serves to keep them in place and apart. On the elongated outer ends of the spur-wheel hubs w' 60 are formed the radial outwardly-projecting arms S' S', which are connected with the traction wheels by means of the links S, one end of which is connected with the hooks q q, bolted 65 to the inside of the rim of the traction-wheel, while the other end connects with the eyebolts r⁵ r⁵, which rest within a suitable sleeve, T, formed on the ends of the radial arms S'.

On the forward or opposite ends of the sleeves 70 T, formed on the ends of the arms S' from the links S and upon the elongated screw ends of the eyebolts r⁵ r⁵, are placed pairs of loose-fitting washer-plates, which embrace the rubber springs i i. The rubber springs and washers 75 are secured in place by nuts, so that the power being applied to the traction-wheels through the medium of the wheels m, the arms S' bear directly upon the springs i i, which therefore receive and neutralize any circumferential shocks the traction-wheels may receive, while the links S S prevent the lateral shocks and wrecks from affecting the wheel m, which is therefore prevented from being injured while 80 the machine is being run over rough and stony 85 roads, thus overcoming one of the greatest difficulties heretofore met with in traction-engines—viz., the breaking of the gear-wheels.

The middle part of the axle o is curved so as to bring the axis of the spindles forward, 90 so that the greater part of the weight of the machine will rest upon the traction-wheels, thereby relieving the steering-wheel B of all weight except just sufficient to give it bite or hold upon the road to guide the machine without slipping, thus rendering the machine easy to handle.

On the top of the main axle o, near the inner ends of the spindles, are secured a pair of pedestals, C' C', the lower ends of which are provided with suitable feet for the purpose, while on the upper ends are formed spring-seats, to

which are secured the springs P P, which in turn support the boiler through the medium of the spring saddle-brackets *ff*, securely bolted thereto. The upper ends of the pedestals C' C' are connected by means of the arch-piece C, the ends of which spring from the spring-seats, as shown. The arch-piece C is also curved backward in the center to nearly correspond with the curvature of the axle *o*, so as to partly encircle the rear side of the boiler, as shown. The right-hand column, pedestal, or pillar C' is curved inward near the top, as shown in Fig. 3, to allow the chain *h* to pass. The axle *o* is connected with the boiler by means of the vertical slotted brackets *o'o'*, which are firmly bolted to said boiler and extend back far enough to embrace the axle within the slots in such a manner as to allow the boiler to swing freely both vertically and laterally. The middle of the arched connecting-piece C is also connected with the middle of the rear side of the boiler by means of the keeper U in a manner to correspond with the slotted brackets *o'o'*, so that the rear end of the machine swings upon the springs with the utmost freedom.

The advantages derived from the use of the columns or pedestals C' C' are that the springs being placed above the gears *m m'*, they can be set farther apart, giving a wider spring-base, saving room, so that a wider boiler can be used without increasing the gage or distance between the traction-wheels. Another advantage gained by this construction is that the springs are raised above the axis of the longitudinal center of gravity of the machine. Hence when the machine is tipped over to one side, as on a laterally inclined roadway, the upper spring will be brought nearest the vertical line of center of gravity. Hence the major part of the weight of the machine will be brought to bear upon the said upper spring, relieving the one on the opposite or lower side, thereby compressing the said upper spring and allowing the opposite one to expand, thus tending to bring the boiler to a vertical position.

To opposite sides of the lower end of the boiler are firmly bolted a pair of stout brackets, *w w*, in the outer ends of which are formed eyes to receive the rear ends of the braces D, D', and G. The forward ends of the braces D, D' are firmly secured to a pair of lugs formed upon the lower end of the caster-shaft sleeve A, while the forward ends of the braces G are connected in the same manner with lugs formed on the upper end of said caster-shaft sleeve A. The forward end of the brace V is also connected with a suitable socket formed on the lower end of the sleeve A, while the rear end is connected with the boiler by means of a suitable socket bolted thereto. The sleeve A is thus held very rigidly and in a position with relation to the boiler of about twenty degrees rearward inclination at the top. The rear ends of the braces D, D', and G, where they pass through the eyes in the brackets *w w*, are

threaded to some distance from the ends and nuts placed on both sides of said bracket-eyes, thus affording a very ready means of adjusting the angle of the caster-shaft sleeve A with relation to the boiler; also, for adjusting the inclination of the vertical axis of the boiler forward or backward, as may be desired.

Within the sleeve A is placed a short shaft, on the lower end of which is formed the large 75 caster-yoke J, to which is pivoted the steering-wheel B, while on the upper end of said shaft is rigidly hung the worm-gear F, which gears with the worm I on the shaft *x'*. The forward end of the shaft *x'* is pivoted to a curved arm 80 springing from the sleeve A, while the rear end is pivoted to an arm, *t'*, on the right-hand side of the seat-casting *t''*, which is rigidly mounted on the brace V, as shown.

The foot-board L is mounted upon and rigidly attached to the braces G and in convenient position with relation to the seat *t''*. A person seated upon the seat *t''* can by turning the crank K on the rear end of the shaft *x'* and within convenient reach turn the axis of 90 the caster wheel B to any position, and thereby guide the machine in any direction. The axis of the caster-yoke shaft being placed at a rear inclined angle from vertical, it is obvious that when the axis of the steering-wheel 95 B is turned out of line with the axis of the traction-wheels, as in turning, only the rearwardly-inclined edge of said steering-wheel will rest upon the ground, thus giving it a better hold and preventing it from slipping or 100 driving forward. The face of the steering-wheel B is made concaved, as shown in Figs. 2 and 3, in order to further overcome the tendency to slip laterally.

From the rear sides of the pedestals C' C' 105 spring respectively a pair of curved arms, *xx*, which connect with and support the sleeve Y, as shown in Fig. 2. The sleeve Y, pedestals C' C', arms *xx*, and the arch-piece C are all cast in one piece, and when bolted to the axle 110 *o* form a strong yet comparatively light frame. The shaft *p* has bearing within the sleeve Y, and upon the left-hand projecting end is rigidly secured the pinion *n'*, which meshes with the spur drive-wheel *m'*, while on the opposite 115 end of said shaft is hung the equational or compensation gear, which consists of the bevel-wheel *m²*, hung fast on the shaft, the sprocket-wheel *g* and the bevel-wheel *m³* both running loose thereon. A bevel-pinion, *a⁴*, is hung 120 within a mortise or recess in the web of the sprocket-wheel *g*, and runs loose upon a radial pin passing across said mortise, so that the said bevel-pinion will mesh in common with both the bevel-wheels *m²* and *m³*.

On the back of the web of the bevel-wheel *m³* is formed or is rigidly attached the spur-pinion *n*, which meshes with and drives the spur drive-wheel *m*, which in turn drives the traction-wheel E, as before described.

The power or motion being communicated to the sprocket-wheel *g* through the medi-

um of the chain h , it is obvious that the said force or power will be equally distributed to the traction wheels by the pinion a^4 , acting on the principle of a balance-beam between the 5 wheels m^3 and m^2 . When the machine is run around curves one wheel must necessarily travel farther than the other, when the pinion a^4 will rotate on its axis, thus allowing the traction-wheels to rotate relatively at different 10 speeds, yet remain tight in gear and assist in driving the machine.

On the main shaft v of the engine are hung fast the different-sized sprocket wheels a and k , which are constructed to receive the friction-chains t and t' , which in turn run on corresponding steps on the friction cone-pulley e d , the faces or steps of which are turned smooth and true and each provided with flanges to prevent the chains from running off. The 20 cone-pulley e d turns loosely upon a stout stud-shaft, r , firmly secured by the inner end within a sleeve formed on the end of a strong bracket bolted to the side of the boiler.

To the outer side of the friction cone-pulley 25 e d is formed or is rigidly secured the sprocket-wheel s , the plane of which corresponds with the plane of the sprocket-wheel g on the shaft p . A sprocket-chain, h , communicates motion from the cone-pulley e d and sprocket s to the 30 wheel g , one part of said chain passing beneath the main axle o , as shown. The axis of the sprocket and pulley d s is placed nearly on a horizontal line with the axis of the counter-shaft p , so that the tension of the chain h will 35 pull nearly at right angles with relation to the motion or play of the boiler with relation to the axle o , so as not to interfere with the action of the carrying-springs P P .

The chains t consist of a series of friction-40 pad links with hooks formed on the ends thereof in such a manner as to receive the square links n^4 , by which they are connected, as shown in Figs. 5 and 6. The friction-pad or face part of the links t^2 is made wider than the connecting-links n^4 , and so as to nearly fill the space between the flanges of the cone-pulley e d . The bars of said connecting-links are thus protected from wear by running against said flanges.

50 In order to prevent the friction-chain faces and the cone-pulley from wearing too rapidly or cutting, I form some or all of the said friction-faces with a chamber therein, which is filled with some metal or composition differing 55 from the material of the link and pulley. This chamber may be made in the form of a large countersunk rivet-hole, and the filling metal made in the form of rivets, with large heads formed to fit, and riveted in, as shown at a' a' , 60 Figs. 6 and 7.

The composition filling in the friction-link faces has the advantage of preventing the chains from adhering to the face of the pulley too suddenly, which in starting the machine 65 would cause unpleasant jerks.

The friction-chains t are run quite loosely on

the pulleys when not tightened by the spools e , so that when the engine is running they will glide around the pulley e d without wear or friction. The sprocket-cone a being about vertical above the said cone e d , the weight of the friction-chain will cause no tension. To the side of the boiler is bolted a stud-pin u , to which are pivoted by means of short sleeves the tightening-arms b and u' , carrying the tightening-spools e and e' , in such a manner that they can be brought to bear against and tighten respectively the friction-chains t and t' .

On the opposite sides of the arms b and u' from the spool-studs are formed short studs, 80 to which are connected respectively the rear ends of the rods R and Q , while the forward ends of said rods are connected with the treadles N and O , pivoted to the foot-board L , and within convenient reach of the feet of the attendant when seated in the seat t'' . By this construction the operator can by pressing lightly on either one of the treadles N O tighten and thus bring into action the respectively-connected friction-chains, and can, when necessary, change or substitute one chain or gear for the other while the engine is traveling.

In practice a number of different-speed trains may be used. In most cases perhaps four would be sufficient. They may be arranged so 95 that, assuming the engine to have a regular motion, the machine will travel at the rate of, say, one, two, four, and six miles per hour. It is obvious that there are many advantages to be derived from the use of speed-gears, especially the devices here shown, as in that the engine may be kept running and the machine may be started forward or backward from any position without danger of the engine stopping suddenly on centers and necessitating 100 the dangerous operation of starting or helping it to start by turning the fly-wheel by hand.

In running over smooth and level roads a fast speed may be used, and thus run as fast 110 as the whole power of the engine will drive the machine along; and when grades or rough places are encountered a slower speed may be instantly and without stopping brought into action, thus augmenting the drawing force of 115 the engine to suit the circumstances.

The platform P^2 is by any suitable means strongly attached to the lower end of the boiler or to parts connected therewith, and extends some distance behind said boiler for the person to stand upon who attends the fire, and also to some distance forward of the engine for standing-room and to protect the said engine from mud and dust from the road.

To the outer edges of the platform P^2 is detachably connected by means of the hook-brackets p^4 p^4 the wheel-cover M , the edge of which is provided with a curved projection, M' , which extends over the wheel, as shown, to prevent said wheel from throwing dirt into the gearing 125 when the machine is running. The wheel-cover M is provided with a slotted opening, which al-

lows it to pass down between the gears m and n and the arms S' , the before-mentioned slotted opening passing over the elongated hub w' of said gear-wheel m , allowing the hook P^4 to rest 5 upon the platform P^2 , as shown, while the upper edge is connected with the boiler by a small rod. The slotted opening in the wheel-cover is extended high enough to allow the axle and wheel sufficient vertical play to accommodate 10 the action of the springs. In order to close the slotted opening in the wheel-cover, I provide a sliding disk, i' , formed of thin wood or of metal, and of a size somewhat longer and wider than the said slotted opening, and provided 15 with a hole near the end a little larger than the hub w' , over which it is placed, as shown in Fig. 4. If the cover i' be of wood, it can be made in two parts, the division arranged to cent the hole therein, so that the parts 20 can be placed together upon the hub and secured by means of cleats or otherwise. The disk i' extends down a little below the edge of the platform P^2 , and is held loosely in place against the inside of the wheel-cover M by 25 means of hooks or ledges in such a manner as to hang loosely upon the hub or sleeve w' , vibrate vertically therewith, and allow the said wheel-cover to be raised upward until it slips clear of the ledges or hooks. The wheel-cover 30 may be thus removed entirely when necessary. Only one side of the machine is here shown as provided with a wheel cover or guard. It is, however, in practice necessary to provide covers for both wheels.

35 It is evident that to handle with safety so unwieldy a machine as a traction-engine must necessarily be a reliable brake device is of the utmost importance. Again, it is evident that brakes constructed in the ordinary way with 40 brake-shoes applied to the faces of the traction-wheels, which must necessarily be supplied with cleats or be otherwise roughened, would hold in a very irregular manner, hence would be unreliable except for the purpose of 45 stopping quickly, as in descending grades. In order to overcome these difficulties I provide two sets of separate and independent brake-gears. One set is arranged with ordinary brake-shoes applied to the faces of the 50 traction-wheels, while the other set is arranged to attain the desired result by means of brake-shoes applied to friction faces formed on or attached to the principal wheels of the equational gear.

55 To the lower edges of the arms x are hung in suitable eyes or bearings the brake-bars k^5 and k^6 . The right-hand projecting end of the bar k^6 is curved around so as to clear the sprocket-wheel g , and down beneath the friction-face b^6 on the bevel-wheel m^3 , where on 60 the end is mounted a suitable brake-shoe arranged to be brought to bear against said friction-face b^6 , while the right-hand end of the bar k^5 is curved directly beneath the opposite friction-face, b^4 , on the bevel-wheel m^2 , where it is also provided with a shoe arranged to bear

against said friction-face b^4 in the same manner. The friction-wheels b^4 and b^5 are formed by extending the respective webs of the equational-gear bevel-wheels m^3 and m^2 and forming 70 a suitable face thereon.

On the opposite ends of the brake-bars k^5 and k^6 are rigidly attached the upward-projecting levers n^6 and n^5 , the upper ends of which are in turn connected respectively with 75 the treadles b^6 and b^5 by means of the rods p^5 and p^6 . The treadles b^6 and b^5 are pivoted to the foot-board L just beneath the forward part of the seat t'' and quite close together, and in such a manner as to oscillate on, or about 80 on, the same axis, but relatively entirely independent of each other, so that the attendant may with one foot operate both treadles at the same time, and thereby apply the brakes to both the friction-wheels b^4 and b^5 at the same 85 time, and thus retard the motion of both traction-wheels; or he may press upon either one of the said treadles, and thereby apply the brake to the respective friction-wheel and connected traction-wheel independent of the other. 90 The objects of this arrangement of independent brakes are to enable the pilot to more easily and effectively guide or steer the machine, especially in turning short curves on uneven ground, as in turning a curve against or up 95 an incline—for instance, say to the left—he can apply the brake to the left-hand traction-wheel. The action of the equational gear will transfer the greater part of the effective power of the engine to right traction-wheel, which 100 will, as will be seen, incline the front of the machine to the left, and thus enable the steering-wheel to mount a steep incline with ease and without slipping.

To the under side of the platform P^2 are 105 hung side by side and by means of suitable bearings the brake-bars k' and k^2 . On the outer ends of each are formed crank-arms, to which are pivoted suitable brake-shoes, as shown. The brake-bar k^2 extends across beneath the platform, and on the opposite end is formed the lever e^2 , which projects upward through an opening in said platform. The other brake-bar only extends far enough beneath the platform to give it sufficient bearing, and is provided with a lever, e' , corresponding with the lever e^2 on the bar k^2 , and which also extends upward through the before-mentioned same opening, as shown.

To the foot-board L are pivoted the levers t^5 and t^6 by means of a single laterally-projecting stud bolted thereto. The lower ends of the levers t^5 and t^6 , which extend some distance below the platform L , are connected with the top ends of the levers e' and e^2 through the medium 115 of rods h' and h^2 , as shown.

To the foot-board L and between the levers t^5 and t^6 is secured the arched segment s^2 , which is notched on both sides or faces, as shown. The lever t^5 is provided with a lip which engages with the teeth of said segment, while the lever t^6 is provided with a swinging yoke, $a^2 a^2$,

9 pivoted thereto, the jaw a^2 of which is provided with an arm, which, when the said yoke is thrown back, as shown in Fig. 7, engages with the teeth on the opposite side of the segment 5 s^2 , as shown, so that either one of the levers and the respectively-connected brakes can be operated independently of the other; or the said yoke may be thrown over so that the jaws embrace the lever t^5 , as shown in Fig. 4, when 10 both levers and both brakes may be operated as one through the lever t^5 . The object of this brake-gear is more especially for a safety-brake, for the purpose of stopping quickly, as when in descending a grade the machine should 15 become unmanageable, and for holding the wheels when the engine is being used as a motor for driving other machinery, thus rendering unnecessary the detachable stays and braces usually bolted to the wheels of mounted engines 20 for the purpose of steadyng them when at work.

By combining independent brakes with equational gear in the manner shown I obtain other important advantages, as, when it 25 is desired to turn quite short with my engine, the pilot applies the brakes quite hard to one of the traction-wheels, so as to hold it fast; then by turning the steering-wheel so that its axis, if extended, would cut about where the 30 fast traction-wheel rests upon the ground, and applying power to the traction-wheels, say, through the slowest gear-train, the machine may be whirled around. The traction-wheel held fast by the brake will act as a pivot, about 35 which the machine may be swung to any position.

It is obvious that the machine can be turned round in this way by running it back or forward, and that by backing around it can be 40 turned on a space of much less radius than the length of the machine.

Having thus fully described my invention, what I claim as new, and desire to secure by Letters Patent, is—

45 1. The combination of the curved axle o ,

pedestals $C C'$, arch-piece C , sleeve Y , slotted brackets $o' o'$, keeper U , springs $P P$, and the boiler W , substantially as and for the purposes herein specified.

2. The combination of the axle o , gear-wheel m , sleeve w' , arms S' , links S , and the traction-wheel E , substantially as and for the purposes herein specified.

3. The combination of the platform P^2 , slotted wheel-cover M , sliding disk i' , and the sleeve-hub w' , all arranged substantially as and for the purposes herein specified.

4. The combination of the arms S' , links S , eyebolts r^5 , sleeves T , springs i , and the traction-wheel E , substantially as and for the purposes herein specified.

5. The combination of the shaft v , sprocket-cone $a k$, smooth cone $e d$, gear s , chains $t t'$, tighteners $c c'$, and the treadles $N O$, substantially as and for the purposes shown and described.

6. The combination of the boiler W , brackets w , threaded rods $D D' G$, brace V , sleeve A , and the caster J , substantially as and for the purposes herein specified.

7. The combination of the caster J , worm-gear F , worm I , shaft x' , crank K , and the seat t'' , substantially as and for the purposes herein specified.

8. The combination of the equational gear-wheels $m^2 m^3$, friction-faces $b^4 b^5$ formed thereon, independent brakes $h^5 h^6$, and the treadles $b^6 b^7$, substantially as and for the purposes herein specified.

9. The steering caster-wheel yoke-sleeve A , having a rearward inclination from vertical at the top with relation to the engine, in combination with the caster-wheel B , provided with a circumferentially-concaved face, substantially in the manner and for the purposes shown and described.

H. H. BRIDENTHAL.
